DAVENPORT HINGED TO FORM A BED

Harold A. Vogel, Detroit, and Helmut E. Bahr, East Detroit, Mich., assignors to No-Sag Spring Company, Warren Township, Mich., a corporation of Michigan

Application September 13, 1951, Serial No. 246,406

4 Claims. (Cl. 5—42)

This invention relates to sofa beds, and particularly to a love seat type bed divan composed of three sections which pull out to make a full size bed.

While bed divans of two and three section type have been employed heretofore in the art, the present type of love seat bed divan embodies substantial improvements over the type heretofore manufactured and sold in the trade.

The main objects of the invention are: to provide a bed divan of the three section type having all of the units interconnected to be moved into bed position by the actuation of one of the units; to provide a bed divan of the three section type employing the simplest type of hinge structure for uniting the three sections in unit relation to each other; to provide stop means on the hinges of the sections to limit the movement thereof into seating and bed positions; to provide a link hinge for supporting the back section of a three section bed divan which lowers the back section to the depth of the two superimposed seating sections so as to project only a minimum amount above the top portion thereof; to project the lower edge of the back section forwardly and the rear edge of the seating section rearwardly when the sections are in seating position to produce a maximum area when in bed position while eliminating any space between the sections when in seating and bed positions; and, in general, to provide a three section bed divan which is simple in construction, positive in operation and economical of manufacture.

Other objects and features of novelty of the invention will be specifically pointed out or will become apparent when referring, for a better understanding of the invention, the following description, taken in conjunction with the accompanying drawings, wherein:

Figure 1 is a view in elevation of a love seat type of bed divan embodying features of the present invention;

Fig. 2 is an enlarged sectional view of the structure illustrated in Fig. 1, taken on the line 2—2 thereof;

Fig. 3 is an enlarged, broken sectional view of the structure illustrated in Fig. 2, taken within the area of the circle 3 thereof;

Fig. 4 is a view of the structure illustrated in Fig. 2, when the three sections thereof are extended into bed position;

Fig. 5 is an enlarged, broken sectional view of the structure illustrated in Fig. 2, taken on the line 5—5 thereof;

Fig. 6 is an enlarged, broken sectional view of the structure illustrated in Fig. 2, taken on the line 6—6 thereof;

Fig. 7 is an enlarged, broken sectional view of the structure illustrated in Fig. 4, taken on the line 7—7 thereof;

Fig. 8 is a view of structure, similar to that illustrated in Fig. 3, showing a further form of the invention;

Fig. 9 is an enlarged broken sectional view of the structure illustrated in Fig. 8, taken on the line 9—9 thereof;

Fig. 10 is a view of structure, similar to that illustrated in Fig. 8, showing a still further form of the invention;

2

Fig. 11 is an enlarged, broken sectional view of the structure illustrated in Fig. 10, taken on the line 11—11 thereof;

Fig. 12 is a view of structure, similar to that illustrated in Fig. 10, showing a still further form of the invention;

Fig. 13 is an enlarged, broken sectional view of the structure illustrated in Fig. 12, taken on the line 13—13 thereof, and

Fig. 14 is a broken view of structure, similar to that illustrated in Fig. 2, showing a still further form of the invention.

Referring to Figs. 1 to 7, the bed divan therein illustrated comprises a box frame 19 having a pair of arms 21 secured thereto to form the main support for the assembly. A back section 20, a forward seating section 23, and an intermediate section 22 are hinged to each other and to the box frame 19 so as to be movable from seating to bed position, as illustrated in Figs. 2 and 4 respectively. The back section 20 has a base frame 24 on which coil springs are mounted in the usual manner and thereafter padded and upholstered to form the back section. In Figs. 2 and 3 it will be noted that the lower end of the back section is extended at 25 so as to have the end wall thereof disposed substantially parallel to the top of the box frame 19 when in seating position and to overhang the base frame 24 when in bed position. Similarly, the forward seating section 23 has a base frame 26 upon which springs are supported, padded and upholstered to produce the seating section. The rear edge of the forward seating section 23 is extended at 27 to overhang the edge of the frame 26 so as to eliminate a gap when in seating position with the back section 20. The intermediate section 22 similarly is built upon a base frame 28 upon which the coil springs are supported, padded and upholstered in the usual manner.

The back section 20 is supported on a pair of link hinges 31 having a flanged plate 32 which is attachable to the box frame 19 and a flanged plate 33 which is attached to the frame 24 of the back section. A pair of links 34 and 35, of predetermined relative length, is pivoted to the respective plates 32 and 33 in such relation as to have the back section 20 disposed at the proper angle when in seating position, as illustrated in Fig. 2, and to have the back section disposed horizontally when in bed position, as illustrated in Fig. 4. A tab 36 is illustrated as being struck from the plate 32 in position to be engaged by the link 35 when the back section is in seating position to position and support the back section. A pair of spring pressed plungers 37 is mounted on the back-board of the box frame 19 to be in position to engage the frame 24 of the back section 20 when in seating position to eliminate the shock which would occur when the back drops into seating position and to assist in the swinging of the back to bed position. Preferably one of the units 37 is provided at each side of the bed divan for balancing the force applied thereto.

Each of the side members 38 of the box frame 19 is provided with a slot 39 in which the top flange of the plate 32 projects for locating the plate on the box frame in which the flange is adjusted between the front and rear members of the box frame. Suitable screws 41 retain the plate in adjusted position. The flange of the plate 33 is secured to the frame 24 of the back section 20 by suitable screws 42.

The intermediate section 22 is secured to the side members 38 by a pair of swivel hinges 43 having a vertical leaf 44 attached to the side members 38 of the frame 19 and a horizontal leaf 45 which is attached to the frame 28 of the section. The horizontal leaf 45 of each hinge has an angle element 46 attached thereto to extend therefrom to form spring supporting arms. The arms have

one end of a spring 47 secured thereto by suitable means, herein illustrated as by a rivet 48, the opposite ends of the springs being secured to the side members 38 of the box frame 19 by screws 49. The angle element 46 provides lever arms of proper length to produce the necessary degree of tension in the spring 47 for aiding in the swinging of the forward seating section 23 from seating to bed position.

The intermediate section 22 is joined to the forward seating section 23 by a jackknife hinge 51, one leaf 52 of the hinge 51 having a flanged edge which engages the frame 28 of the intermediate section 22 to which it is secured by suitable screws 53. A similar leaf 54 has its flange attached to the frame 26 of the intermediate section 22 by suitable screws 53. The two leaves 52 and 54 are hinged together by pivots 55 below the bottom of the frame 26 and 28, as illustrated in Fig. 4. A tongue 57 is struck outwardly from each of the plates 54 to be in abutting relation when the two sections 22 and 23 are in horizontal alignment with each other in bed position. The abutment of the flanges 57 is illustrated in the enlarged view of Fig. 7.

The leaf 54 has a leg 58 welded thereto in right-angle relation to the frame 26 of the forward seating section 23 so as to have the end thereof engage the floor when in bed and seating positions. Further support is provided by the leg 59 which is pivoted to a plate 61 secured to the frame 26 of the forward seating section 23. The leg is joined by a rod 62 to the hinge 51 in a manner to have the leg moved into the position illustrated in Fig. 2 when the seat sections are disposed in seating position.

A strip of fabric 63 extends from the back lower edge of the back section 20 to which it is secured by tacks or other means across the top of the intermediate section 22 when in bed position, downwardly over the forward end thereof, and secured to the frame 28 by suitable means, as by tacking. The strip of fabric 63 moves the bottom edge of the back section 24 forwardly when the front and intermediate sections are swung out to bed position, thereby moving the back section to bed position all by the single manipulation of the forward seating section 23. The forward seating section 23 is provided with a finish strip 65 along its front end in position to rest upon the front board 66 of the box frame 19 when the divan is in seating position, as illustrated in Fig. 2. The finish strip 65 is grasped near the center when the forward seating section 23 is to be raised, which is permitted by the notch 67 formed in the board 66, and the forward seating section 23 is pulled forwardly to swing the intermediate section 22 on the swivel hinge 43 as the jackknife hinge 51 moves into extended position. Near the end of this movement, the fabric strip 63 stretches over the top of the intermediate section 22 and pulls the lower edge of the back section 20 forwardly and aligns the section with the sections 22 and 23 in bed position. It will be noted that the projecting edges 25 and 27 of the sections 20 and 23, respectively, are disposed adjacent to the edge of the intermediate section 22 in bed position to eliminate any gap therebetween. It will be noted also when in bed position that the back section 20 rests upon the back-board of the box frame 19 and is supported at the sides on the links 34 and 35 and at the front edge by the fabric strip 63. The intermediate section 22 has its rear edge resting upon the swivel hinge 43, with its forward edge retained in position by the flanges 57 disposed in abutted relation on the jackknife hinge 51. The jackknife hinges are directly supported by the leg 58 and the forward seating section 23 as further supported by the pair of legs 59, one disposed on each side of the section. It is to be understood that the structure recited above for the one side of the divan sections is also employed on the opposite side thereof.

When the sections are to be moved from bed position to seating position, the finish strip 65 on the section 23

is again grasped to raise the two sections 22 and 23 upwardly, after which the forward edge of the forward seating section 23 is dropped to cause the hinge 51 to fold, which occurs as the intermediate section 22 swings about the swivel hinge against the forward edge 25 of the back section 20. When this occurs, the back section 20 swings on the links 34 and 35 of the hinge 31 to upright or seating position. The end of this swinging movement of the back section 20 is cushioned by the buffer devices 37 supported on the rear board of the box frame 19. When in seating position, it will be noted that the back section 20 extends downwardly the full depth of both of the sections 22 and 23 to provide a low back type of divan.

The upper end of the back section 20 has wing portions 68 and the arms 21 have a recess 69 on their inner surface at the rear edge thereof. The wing extensions 68 move within the recesses 69 when moved to and from seating position and mate with the arms and cover the recess portions 69 thereof when in seating position.

Referring to Figs. 8 and 9, a further form of the invention is illustrated, that wherein a strap 71, attached to the jackknife hinge 51, is utilized in place of the fixed leg 58. An angle bracket 72, welded to the leaf 52 of the link hinge 31, has an outwardly extending flange 73 which is engaged by a flange 74 on the end of the strap 71, as illustrated more clearly in Fig. 9. When the forward seating section 23 is in seating position, the flange 74 rests on the flange 73 and provides support for the section at each side of the divan.

In Figs. 10 and 11, a further form of support is illustrated, that wherein a strap 75 is welded directly to the link 35 to have the upper end disposed in position to engage the end of the rod 62 when the sections are in seating position.

In Figs. 12 and 13, a further form of support is illustrated, that wherein a strap 76 is welded to a leaf of the jackknife hinge 51 and extends rearwardly in position to engage a block 77 on the link 35, as illustrated in the figures. When in seating position, the end of the strap 76 contacts the top of the block 77 and thereby provides support for the rear end of the seat section. The end 78 of the strap is bent outwardly to provide a cam surface which cams the strap outwardly when the end engages the adjacent edge of the link 35.

In Fig. 14, a further form of the invention is illustrated, that wherein the box frame 19 has a plurality of metal straps 79 extending across the bottom from the front to the rear thereof. The top of the intermediate section 22 rests upon the straps and thereby provides support for the pad and upholstering material which prevents them from sagging from the supporting springs when in inverted position.

It will thus be seen that a bed divan has been provided having a comfortable seating area which rests against a back section which extends down the full depth of the two seating sections so as to provide a low appearance. Wings are provided on the back section to extend beyond the inner spacing of the arms which are recessed at the rear to receive the wings. The wings provide an appearance of solid construction to the back section, the same as in the built-up type of divan. Spring operated bumpers are also provided at the rear of the box frame against which the back section strikes as it swings to seating position and which is available to assist initially to urge the section outwardly to bed position.

Various supports are illustrated for the rear edge of the top section when in seating position, which are attached to the jackknife hinge. In one form, a leg is directly attached in floor-engaging position. In another form, a strap on the hinge engages a plate on the link of the back section hinge or which may engage a block welded or otherwise secured thereto. Metal straps may be secured between the front and rear frame elements of the box frame upon which the intermediate cushion rests.

A strip of fabric is preferably attached to the intermediate section and to the rear edge of the back section in such manner as to pull the back section from seating to bed position when the intermediate cushion is moved to bed position. The hardware employed for pivoting the three sections is simple in construction, requiring no locks or latches, which results in a rugged assembly which is always operative. The sections are retained in abutting relation by providing overhanging edges on the bottom of the back section and at the top of the rear edge of the front section.

What is claimed is:

1. A bed divan comprising when in bed position a box frame having arms at each end thereof, a back section, a forward seating section, an intermediate section, link hinges connecting the sides of the back section to the sides of the box frame, swivel hinges connecting the sides of the intermediate section to the sides of the box frame, hinges connecting the intermediate section to the forward seating section, and a fabric strip connecting the rear portion of the intermediate section to the lower portion of the back section when in seating position to cause the latter to move to bed position when the intermediate section is moved to bed position with said fabric strip extending across the top surface thereof.

2. A bed divan comprising when in bed position a box frame having arms at each end thereof, a back section, a forward seating section, an intermediate section, link hinges connecting the sides of the back section to the sides of the box frames, swivel hinges connecting the sides of the intermediate section to the sides of the box frame, jackknife hinges connecting the intermediate section to the forward seating section, spring supporting arms extending forwardly from the swivel hinges and secured to the forward edge of the intermediate section when the sections are in seating position, and springs connecting the end of each of the last said arms to the sides of the box frame to assist the forward swinging of the intermediate section and to cushion the movement of the intermediate section when moved to seating position.

3. A bed divan comprising a box frame having arms at each end thereof, a back section, a forward seating section, an intermediate section, link hinges connecting the sides of the back section to the sides of the box frame,

10

swivel hinges connecting the sides of the intermediate section to the sides of the box frame, jackknife hinges connecting the intermediate section to the forward seating section, and wing extensions provided upon the back section above the arms on each side thereof, said arms at the rear being recessed to receive said wing extensions when the back section is moved to bed position.

4. A bed divan comprising a base frame having thereon a back section, an intermediate section, and a forward seating section, means for supporting the back section on said base frame for movement from bed position to back rest position, means supporting said intermediate section for arcuate swinging movement through substantially 180°, hinge means securing the forward seating section to the forward edge of the intermediate section when the sections are in bed position, and a fabric strip secured to the forward edge of the intermediate section when in bed position and extended over the top of said intermediate section and secured to the forward portion of the back section.
